UNITED STATES PATENT OFFICE

90,871

DESIGN FOR A COMBINED COIN TRAY AND DISPLAY RACK

James W. Critchfield, Pittsburgh, Pa., assignor
to Clark Brothers Chewing Gum Company,
Pittsburgh, Pa., a corporation of Pennsylvania

Application April 28, 1933. Serial No. 47,927

Term of patent 3½ years

To all whom it may concern:

Be it known that I, JAMES W. CRITCHFIELD, a citizen of the United States of America, residing at North Side, Pittsburgh, in the county of Allegheny and State of Pennsylvania, have invented a new, original, and ornamental Design for a Combined Coin Tray and Display Rack, of which the following is a specification, reference being had to the accompanying drawing forming a part thereof.

Figure 1 is a top plan view.

Figure 2 is an elevation.

Figure 3 is a sectional view.

Figure 4 is a perspective view of the same.

I claim:

The ornamental design for a combined coin tray and display rack as shown.

JAMES W. CRITCHFIELD.
